CONGA DRUM

Sam U. Lane, 1675 N. Teilman Ave., Apt. B,
Fresno, Calif. 93705

Filed Apr. 23, 1973, Ser. No. 353,410

Term of patent 14 years

Int. Cl. D17—04

U.S. Cl. D56—1 E

FIG. 1.

FIG. 3.

FIG. 2.

FIG. 4.

FIG. 1 is a top plan view of a conga drum showing my new design.

FIG. 2 is a side elevational view thereof, the opposite side being identical.

FIG. 3 is a bottom plan view.

FIG. 4 is a perspective view.

I claim:

The ornamental design for a conga drum, as shown and described.
